UNITED STATES PATENT OFFICE.

EDWARD E. TAYLOR, OF NEWPORT, RHODE ISLAND, ASSIGNOR OF
ONE-HALF TO JAMES S. HAZARD, OF SAME PLACE.

COMBINED BARREL CLAMP AND HOOK.

SPECIFICATION forming part of Letters Patent No. 336,357, dated February 16, 1886.

Application filed October 28, 1885. Serial No. 181,140. (No model.)

To all whom it may concern:

Be it known that I, EDWARD E. TAYLOR, a citizen of the United States, residing at Newport, in the county of Newport and State of Rhode Island, have invented a certain new and useful Combined Barrel Clamp and Hook, of which the following is a full, clear, and exact description.

This invention relates to certain improvements in a combined barrel clamp and hook, particularly intended for use in hoisting barrels, casks, and the like, but capable of use in hoisting other merchandise.

In the accompanying drawings, in the several figures of which like parts are designated by similar letters of reference, Figure 1 is a side view of a barrel suspended by two of my barrel-clamps, and showing the method of hoisting when the hook-shaped ends are employed to grasp the barrel. Fig. 2 is a similar view of a barrel, showing by full lines how the barrel can be hoisted when only one clamp is used, and by dotted lines how it can be kept in an upright position during the hoisting operation when two clamps are used, and the barrel is grasped by the jaws of the clamp or clamps in both cases. Fig. 3 is a perspective view of my combined barrel clamp and hook, which consists of two arms pivotally connected at *a* to form jaws *b* *c* and handle portions *b'* *c'*. The jaws are serrated, roughened, or provided with teeth *d*, so that when pressed together they will embed themselves in or take firm hold of anything placed between them—such as the chine of a barrel, for instance. The end of the jaw *c* is backwardly curved to form a hook, *e*, and the handle portions of both jaws are provided with openings, through which the hoisting-rope can be inserted.

Heretofore barrel-hooks have been employed for hoisting and lifting barrels, casks, and the like, which consisted of a single arm with a hook-shaped end like the hook *e*. In some cases they have been provided with a handle which could be grasped by the hand; but usually the arm was merely a straight rod provided with an eye through which the rope could be passed. In hoisting or lifting by such hooks, whether a rope was employed or not, it was always necessary to use two hooks, and to raise the barrel in the manner as

shown by Fig. 1 of the drawings, from which it will be seen that the barrel was always suspended in a horizontal position. This method of hoisting a barrel has often been found inconvenient and objectionable, in that two hooks were always required, and even then a barrel open at one end, whether filled or partially empty, could not be hoisted in this way, as the contents would be spilled out.

To overcome these objections, and still retain all the advantages of the old system of hoisting, I have devised my present improvement, wherein I combine in one device the hook heretofore in use and a pair of clamping-jaws, by means of which a barrel or cask can be kept during the hoisting operation either in an upright or a horizontal position, as may be desired, and a barrel can be hoisted by one of my clamps, as shown by full lines in Fig. 2. When a barrel or cask is to be hoisted in the old way, the chines are grasped by the hooks *e* of two of my clamps, which are connected by a rope, *f*, which is in turn connected at about its center to the hook *g* of the hoisting-rope, as shown in Fig. 1. When a barrel or cask is to be hoisted while upright, or so nearly upright that there is no liability of the contents being spilled, one or two clamps may be employed, the chine at one end of the barrel or cask being grasped by the jaws of one or both clamps, and the jaws clamped together to firmly seize the chine by a rope, *h*, or the hook of the hoisting-rope, which is in either case passed through the openings in the handle portions *c'* *b'*, as shown by full and dotted lines in Fig. 2.

My combined barrel clamp and hook has another advantage over the old style of hook for hoisting purposes in that it can be used for hoisting bags, boxes, and packages of merchandise of various kinds which have a surface which can be seized by the clamping-jaws without liability of damage to the contents.

My combined barrel clamp and hook is simple in construction and operation, and can be manufactured at a small initial cost, and will be found very useful for hoisting purposes.

What I claim as my invention, and desire to secure by Letters Patent, is—

1. A device for hoisting purposes, compris-

ing the clamping-jaws *b c*, having serrated, roughened, or toothed faces, and a hook, *e*, as set forth.

2. A combined barrel clamp and hook for 5 hoisting purposes, consisting of two arms, one of which terminates in a hook, *e*, pivotally connected to form clamping jaws *b c* and handle portions *b' c'*, said clamping jaws having serrated, roughened, or toothed faces, as set forth.

In testimony whereof I have hereunto set my hand this 15th day of October, A. D. 1885.

EDWARD E. TAYLOR.
